INVENTOR

UNITED STATES PATENT OFFICE.

ALBERT E. GREENE, OF SEATTLE, WASHINGTON.

COMBINATION INDUCTION FURNACE.

Application filed January 3, 1913, Serial No. 740,034. Renewed December 19, 1917. Serial No. 207,966.

My present invention relates to improvements in electrical induction furnaces and combination transformer furnaces.

It has been suggested heretofore to combine the induction heating principle of heating melted metal with some other form of resistance heating to supply additional heat in local parts of the furnace. My present invention provides a very simple and novel means of obtaining current for an arc or other resistance heating circuit in combination with means for inducing current in a single turn secondary circuit of an induction furnace, without the use of a separate transformer or a special secondary winding on the induction furnace. My invention contemplates a process and apparatus for heating a bath of molten metal by current induced therein by means of a magnetic core encircling said bath, the core being magnetized by current in a primary winding; and it further contemplates a process and apparatus for generating heat independently of the induction current heating, and of connecting a suitable number of turns of portions of the primary winding on said transformer core in series with an arc or with electrodes, or with some other form of electrical resistance to heat the charge.

One object of my invention is a combination transformer and electric furnace, the transformer of which constitutes an auto transformer whereby the apparatus may be connected to a standard voltage power circuit and at the same time a desired proportion of the winding may be connected to an electrode circuit for generating heat in an arc or other resistance.

A further object of my invention is a combination auto-transformer and electric furnace having adjustable electrodes and means for varying the electrode voltage taken from the transformer winding.

A still further object of my invention is an apparatus combining an electric furnace and an auto-transformer suitable for operation from a comparatively constant voltage source of current, and means for regulating the number of turns of the transformer winding in series with the supply voltage, thereby regulating the induced single turn voltage, and also in certain cases, regulating the number of turns of the auto-transformer which are connected to the electrode circuit.

One purpose of my invention is to use

a single transformer core in combination with an electric furnace, and a primary winding on said core whereby current may be induced in a single turn secondary circuit around the same core, and at the same time whereby current may be drawn from this primary winding, and led to an electrode circuit operating in the same furnace.

A further modification of my invention consists in a polyphase transformer core in combination with a furnace, and comprising windings on the core, one for each phase connected in star, the separate windings for each phase having taps whereby the number of turns connected between the common or neutral point and the supply circuit can be adjusted and whereby also the number of turns of winding connected to electrodes can also be adjusted to give the desired voltages between electrodes. This combination provides therefore, means of adjusting the single turn voltage which voltage may be used in a single turn heating circuit around the core leg; and of independently adjusting the number of turns connected to electrodes and therefore adjusting the electrode to electrode voltages.

One feature of my invention is the combination of a channel for holding molten metal encircling a magnetic core, and a primary winding on the core with a portion thereof enlarged so that a heavy current may be drawn from this portion of the winding by means of taps connecting this portion of the winding to electrodes or to some form of electrical resistance.

A further feature of my invention relates to the method of control of the voltage induced in the induction furnace molten secondary circuit and the voltage of the current tapped from the windings of the primary and led to some suitable electrical resistance.

In one embodiment of my invention polyphase current is applied to the primary windings on the magnetic core or cores for inducing currents in molten metal secondary circuits encircling said cores, portions of the primary windings being provided with additional cross-sectional area of copper and taps taken off these portions of the primary windings and connected in series with suitable resistance for generating heat.

These and other features of my invention will be described with reference to the annexed drawings.

Fig. 1 is a sectional elevation of a single phase electric furnace embodying my invention;

Fig. 2 is a diagrammatic plan view of a three-phase furnace embodying my invention; and

Fig. 3 is a diagrammatic plan view of a two-phase furnace embodying my invention and which is supplied with three-phase current.

Fig. 4 is a diagrammatic view of a three-phase combination transformer furnace showing the taps on the windings for obtaining different voltages between electrodes, and also different voltages between each electrode and the neutral point of the star connected auto transformer.

In Fig. 1 I have shown a furnace which is suitable for the reduction of ore and the heating of the reduced metal in accordance with my invention. A primary winding 1 is wound around a magnetic core 2 and is connected to a source of supply of single phase alternating current. Around the magnetic core is a refractory crucible with a channel 3 encircling this core for holding the single turn molten metal secondary circuit of the induction furnace. One portion of this channel is enlarged to form a pot 4 in which the ore is reduced and melted. This pot is made in the crucible or bottom of a shaft which may be designed in any suitable way. Into the top of this shaft extends an electrode 5 and in the bottom lining is an electrode 6. The primary winding is provided with a portion 7 which consists of a suitable number of turns of copper or other conductor shown in the drawing as four complete turns. One terminal of the primary coil 1 is connected by means of the wire 8 to the source of supply of alternating current and this same terminal is also connected by means of the conductor 9 to the bottom electrode of the furnace. Taps are shown as taken off the four lower turns which constitute the heavy portion of the primary winding and any number of these turns may be connected to the top electrode 5 by means of the switch 10. In this way it is possible to apply any desired voltage to the arc furnace circuit between the bottom electrode 6 and the top electrode 5.

When the primary coil 1 is connected to a constant voltage circuit, as for example, to a 440 volt line, I may by means of taps, any one of which may be connected to the switch 11, vary the potential induced in the molten metal secondary circuit. The current induced in the molten metal consequently may be controlled by means of the taps connected to the switch 11 independently of the voltage applied between the electrodes 5 and 6 thru the controlling switch 10. As to the exact number of turns to be used in each case, this

forms no part of my invention since it is determined entirely by the several voltages which it is desired to use in the induction current circuit and in the resistance circuit. The arc circuit may be of very high potential if desired, therefore requiring more turns on the winding than needed for the induced voltages in the molten bath.

In the operation of this furnace shown in Fig. 1 using both the arc circuit and also the induction heating, I may start with a molten charge and then add ore on top of this in the main pot, or shaft, or crucible, 4, the molten metal being kept heated to the desired temperature by the currents induced therein. The ore charged into the shaft 4 is heated by means of an arc and resistance heating from the top electrode to the bottom electrode, and as above stated, the power, and consequently the temperature developed in the two parts of the furnace, namely the resistance portion and the induction current portion, may be controlled and regulated separately and independently of each other. The electrode circuit is in no way dependent on the induction heating circuit. In fact, one feature of my invention is the combination of a transformer which may be used to induce current in a secondary single turn heating circuit with means of controlling the single turn induced voltage, and means of taking current from that transformer, from a suitable winding on it and by means of taps connecting this winding or a suitable proportion of it to electrodes or some form of electrical resistance, without any limitation as to where the electrode circuit be located.

However, in the operation above described in the furnace of Fig. 1, it is to be noted that the charge is first heated by means of current in the arc circuit from the top electrode 5 to the bottom electrode 6, the arc terminating of course on the charge resting on the bottom of the crucible. After the charge is heated and melted by the heat from the arc, the molten charge then enters the bath below and becomes a part of the induction circuit and has current induced therein. The development of heat in the molten bath is by means of a relatively low voltage current. In the diagram of the windings shown in Fig. 1, there are about 20 turns on the winding which can be connected to the 440 volt supply circuit for example, thus inducing a single turn voltage of some 20 volts or more. Without making allowance for magnetic leakage, the single turn secondary induced voltage would be in the neighborhood of 20 volts; and if four of the twenty turns of the winding were connected to the electrodes the electrode voltage under the above conditions would be about 80 volts. Under these conditions the arc circuit would serve to melt the charge with about an 80 volt arc circuit and then

the melted charge would have current induced in it at a much lower voltage. It is understood that any desired voltage may be applied to the arc circuit and the arc circuit 5 may be of relatively high potential requiring more turns of the winding connected to it. For example, if the supply circuit be 110 volts and a voltage of 130 volts is desired for the arc circuit, then more turns 10 would be required on the winding for the arc circuit than would be required for the induced single turn secondary circuit.

Considering the transformer and electrode circuits shown in Fig. 1 independently of the 15 secondary induction circuit, the transformer shown in this Fig. 1 connected to the arc circuit in fact constitutes an auto-transformer by means of the connections with the supply circuit and with the electrodes. 20 The number of windings connected between the supply lines may be varied by switch 11. In the same manner the switch 10 controls the number of windings connected to the electrodes 5 and 6. The upper electrode is 25 adjustable in elevation by means of the flexible suspension which passes over the pulley mounted on an axis shown in Fig. 1, whereby the electrode may be raised or lowered. The lower electrode 6 passes thru the bottom 30 of the electric furnace chamber so that its upper end will be exposed in position to come in contact with the molten metal or other charge.

It will thus be seen that Fig. 1 shows an 35 electric furnace adapted to heat a charge by means of heat generated by the current from the electrodes 5 and 6 entering the heating chamber. The current is supplied to the electrodes by means of an auto transformer. By manipulating switch 10 or switch 11, or both, the potential between the electrodes may be varied in accordance with operating conditions; or in other words by way of example, if the voltage first tried is 40 not high enough to force the desired current thru the resistance, obviously the voltage may be increased by means of the switches 10 or 11 or both and vice versa. Furthermore the upper electrode may be adjusted in 45 elevation to vary the resistance between the electrodes 5 and 6 and thereby vary the current flowing thru the electrodes. By means of the switch 11 the number of turns of the windings of the transformer connected to the source of alternating current supply may 50 be varied; and furthermore, the number of windings of the transformer connected to the electrodes may be varied by the switch 10. The switch 11 will vary the single turn induced voltage and the switch 10 will vary 55 the number of turns connected to the electrodes. Obviously the switch 11 will vary the voltage applied to the electrodes for any given connection of switch 10.

In Fig. 2 is shown a polyphase auto-

transformer which is arranged to supply current to a plurality of electrodes entering the heating chamber. By supplying each of the separate windings shown in Fig. 2 with switches similar to those indicated at 10 and 11 in Fig. 1, the electrodes shown in Fig. 2, at 25, 26 and 27 may be connected to the separate phases of the polyphase auto-transformer. Furthermore, each of the electrodes 25, 26 and 27 may be made adjustable in elevation in the manner illustrated in Fig. 1.

It should be understood that while Fig. 2 shows three interconnected cores 15, 16 and 17 and interconnected passages 29, 30 and 31 corresponding to the induction circuit 3 35 of Fig. 1, the polyphase auto-transformer and electrode circuits will operate entirely independently of the induction circuits.

In Fig. 3 I have shown two magnetic cores 40, 40 each with windings thereon to 40 constitute auto-transformers. These windings are connected to a source of alternating current, indicated at 44. The windings 42 and 43 are connected to three electrodes 48, 49 and 50, two of which enter the heating chamber from above, and that designated 50 entering the heating chamber thru one of its upright walls or thru the bottom in a manner similar to that indicated at 6 in Fig. 1. The two separate windings 42 and 43 are interconnected to separate phases of a polyphase supply circuit.

However, when the furnace of Fig. 3 is operated as an arc induction furnace, the arc circuit and the induction circuit are energized from the same transformer and they are also in this Fig. 3 energized from the same winding, on a magnetic core attached to the furnace. In other words Fig. 3 shows an induction arc furnace comprising a plurality of magnetic cores and secondary channels in refractory material surrounding each core. Each core has a primary winding thereon and the induction channels connect with the main chamber into which the electrodes project. In fact both the arrangement shown in Fig. 2 and the arrangement shown in Fig. 3, both include an arc induction furnace operating from a three phase supply circuit and each furnace comprises a plurality of magnetic cores with windings on each core connected to the electrodes which enter the furnace and arranged so that current will be induced in the molten metal secondary circuits. It should be observed that in Figs. 1, 2 and 3 the cores of the transformer encircle or are interlooped with the encircling passages or the closed induction circuits of the molten metal.

Fig. 1 shows diagrammatically a single phase furnace. The transformer winding is provided with two sets of taps, one set being connected to one of the supply lines, and the other set being connected to the up-

per electrode 5. By means of these sets of taps and the switches 10 and 11 the ratio of the voltage applied to the electrodes 5 and 6 to the voltage applied to the winding 1 from the source of supply may be regulated.

When the transformer winding 1 is energized so that a given voltage is generated in such winding any given proportion of this total transformer voltage may be applied to the electrodes 5 and 6 by connecting the switch 10 to the desired tap of those taps connected to the heavier portion of the windings 7, which are of larger cross section.

By means of the switch 11 and the taps associated therewith it is possible to apply the given supply line voltage either to the whole winding 1 or the supply line voltage may be applied to the desired proportion of the winding 1. Thus it is possible to vary and control the voltage of the transformer winding within the limits of the apparatus.

The inherent regulation of the transformer will depend upon its design. If there be considerable leakage of magnetic flux there may be a lowering of the induced voltage applied to the electrode circuit, as the current thru the electrode circuit increases. This drop in voltage may be augmented or off-set by the independent means of voltage control by means of the taps on the windings. Thus when the upper electrode 5 is lowered and the current thru it increases, the voltage between the electrodes 5 and 6 will drop due to the inherent reactance and resistance of the transformer circuits but the electrode voltage may be regulated independently of this drop by means of the switches 10 and 11 or either of them. Thus, for example, if the inherent reactance of the transformer is high, and a given voltage is applied across the electrodes 5 and 6 and this voltage is found to be too low to force the desired current thru the resistance, then the electrode voltage may be raised by means of the switches 11 or 10.

The arrangements shown in the drawings provide for regulation of the voltage so that either a high voltage or a low voltage arc may be used, or the voltage on the electrode circuit may be made so low that the heating is largely by resistance. An arc of suitable voltage may be used in one stage, for example in melting the charge in the shaft of the furnace of Fig. 1, and then after the charge is melted it may be kept heated or further heated by means of low voltage current thru it as a resistor.

Fig. 2 shows a polyphase arc electric furnace comprising a plurality of arcing electrodes and when the auto-transformers as shown in this view are supplied with switches corresponding to those indicated at 10 and 11 in Fig. 1, the current or voltage

of any one arc may be regulated as already described with regard to Fig. 1. In fact the voltage supplied to any one electrode may be regulated by the switch in the circuit to that electrode.

In a furnace in which the induction and arc circuits are used simultaneously it may be necessary to use both sets of switches, one serving to control the induced single turn voltage and the other set to control the electrode voltage.

My invention may be applied in a 3 phase furnace as shown in Fig. 2. A suitable core having three legs shown in plan at 15, 16 and 17 is provided and a primary winding or windings are shown as connected in star or Y and having a neutral or common connection 18 and three terminals 19, 20 and 21 which go to the 3 phase source of power. The neutral connection is of suitably heavy cross sectional area to carry the heavy currents which may be drawn from the heavy portions of the three windings 22, 23 and 24, and the current taken from the taps on these windings may be led to electrodes 25, 26 and 27 between which the power may be applied in any desired way to heat the ore or to heat a bath of metal. The neutral wire 18 may also be connected to a neutral bottom electrode 28 if desired.

The secondary channels holding the molten metal are shown at 29, 30 and 31, encircling the several legs of the magnetic core and uniting in a main chamber 32.

In Fig. 2 the cores shown at 15, 16 and 17 are the vertical legs of a single polyphase (in this case three-phase) magnetic core. These vertical legs are connected together at the top and bottom to form the complete magnetic circuits, which encircle portions of the molten metal in the induction channels. It will be seen that the metal in channel 29 forms a part of a single turn circuit around core leg 15; likewise the metal in channel 30 forms part of a single turn circuit around core leg 16; and also the metal in channel 31 forms part of a single turn circuit around core leg 17.

It will be seen that a vertical section through these vertical core legs and corresponding channels would show four sections of the channels, or in other words, a section of each of four different channels, this number being one more than the number of vertical core legs. Fig. 4, shows approximately what such a vertical section would be like, and also shows the arrangement of the taps above mentioned in connection with the winding on each phase of the core.

It is understood that where I have referred to copper in this specification that I may use any suitable electrical conductor for carrying the current.

With reference to the three phase furnace, shown in Fig. 2, and also in Fig. 4, it

should be noted that this furnace constitutes a combination three phase auto transformer, and a three electrode furnace, and as already mentioned in reference to Fig. 1, this three-phase furnace may be operated as an arc furnace or as an induction furnace, or both methods of heating may be used together, and the heat developed in the arc circuits may be controlled as desired independently of heat developed in the induction circuits, and likewise the development of heat in the induction current circuits may be controlled as desired independently of current through the arc circuits.

In the use of 3 phase current, the primary windings may be connected in delta instead of star and the terminals from the heavy sections of the primary may be led to suitable electrodes for generating an arc or other form of resistance heat. The several voltages may be controlled independently of each other as shown in Fig. 1.

My invention may be used in a 2 phase furnace, as shown in Fig. 3, having two separate cores 40 with primary windings thereon 42 and 43. In the furnace shown, the connections are arranged to take power from a 3 phase circuit 44 and to transform this in the electrical part of the furnace to 2 phase power. For this purpose the approximate center of the primary 42 is connected to one end of the primary 43 and the number of turns so connected are such as will give the desired voltages in the secondary induction circuits of the furnace. The connection between the two coils is made of a suitably heavy conductor and a heavy portion of each winding is provided from the two terminals of this connecting conductor 45. From the other terminals of these two portions 46 and 47 of the primary windings, conductors are taken to the electrodes 48 and 49, and if desired, a neutral electrode 50 may be connected in any suitable way either in the bottom of the lining of the furnace or as a bottom electrode. Thus there will be a current flow between the electrodes 50 and 48, and 50 and 49, and also between the two electrodes 48 and 49.

In Fig. 4 I have shown a diagram of the windings and electrode circuits for a star connected 3 phase auto-transformer furnace combination. The three primary windings are shown at 51, 52 and 53 and they are connected together by a neutral connection 54. Three movable electrodes are shown at 55, 56 and 57 adjustable in elevation, and these have conductors leading to switches so that the number of turns of the winding between the neutral and the connection to the electrode may be adjusted. This would be done in the same manner as for the single phase furnace of Fig. 1. I have also shown the taps on these same primaries which serve to connect the desired proportion of

the total winding to the corresponding conductor of the power circuit and have shown three switches 11' for this purpose. Switches 10' serve to connect the taps desired to the three electrodes respectively. The bottom electrode 28' may be connected to the neutral connection 54 if desired. I have shown also four sections, 115, 116, 117 and 118 which diagrammatically represent the sections of the metal in the single turn induction circuits similar to sections 29, 30, 31 and 32 of Fig. 2 and have also shown back of the windings the general arrangement of the three-phase core having three vertical legs and connecting yokes above and beneath. This construction of apparatus is very inexpensive to construct and is efficient to operate and has very great advantages over any other furnace apparatus heretofore used.

It is understood that the several details of my invention may be applied in any combination of the methods described herein.

It is also understood that I do not limit myself to making the separate heating circuit of less or greater voltage than the supply circuit.

The term "arc circuit" as used in this specification and claims is intended to include any circuit in which the current passes to the charge through an electrode as well as circuits in which the arc constitutes the essential resistance and is not limited to the formation of an arc above the charge, since when an electrode makes contact with a slag or other charge it may happen that no visible arc is formed, yet the term "arc circuit" is intended to include such a circuit.

One of the important advantages of my present invention is that it provides an apparatus which will serve as an induction furnace to heat a single turn secondary circuit and at the same time current may be transformed in the same apparatus and used in an independent electric heating circuit. Thus where before my invention it was customary to provide a transformer to supply current to electrodes and an independent transformer to supply current to the single turn induction circuit, my present invention makes it possible to use the transformer of the induction furnace to supply both circuits and yet control either separately and independently of the other. In other words the two separate circuits are energized from the same transformer.

While I have described the heating and melting and reduction of a charge of ore, it is to be understood that my invention is not by any means limited to such use but may be applied for heating or melting any kind of material or metal within the limits of the apparatus. I have used the term "resistance" to include arc circuits.

The determination of the proper voltage

to use between electrodes of the electrode circuit is a matter dependent on the particular treatment desired, and the range of voltage to be used may be from a very high arc voltage down to practically nothing, and includes very low arc voltages. The voltage may be so low across the electrodes as to avoid much of any arcing. The use of a low voltage in the treatment of metal is described in my copending application for patent Serial No. 470,336 filed Jan. 2, 1909.

I claim:

1. In an electric furnace, the combination of a channel for holding molten metal encircling a magnetic core, a primary winding thereon, means of connecting this winding to a source of alternating current power, and means of connecting portions of the winding to an arc circuit for generating heat in the furnace.
2. In an electric induction furnace, the combination of a channel forming a single turn secondary circuit, a core encircling same with a primary winding thereon, taps on the primary for connecting to electrodes, the portion of the primary between said taps being made of suitable cross-section to carry heavy currents.
3. In a polyphase induction furnace, the combination of a plurality of secondary channels, magnetic cores encircling these channels with primary windings thereon, these windings being interconnected to take polyphase current and provided with taps for supplying currents to an electrical arc circuit for generating additional heat.
4. In a polyphase induction furnace, the combination of secondary channels, cores encircling these with primary coils thereon, the primary coils being provided with suitable turns for carrying additional current and taps on these sections for taking current at the desired voltage to electrodes for additional heating.
5. In an electric induction furnace, the combination of a magnetic core and refractory channel encircling same, of a primary winding on the core, means of connecting a variable number of turns to a source of alternating current, and independent means for connecting a variable number of turns to an electric arc circuit for generating additional heat in the furnace chamber.
6. In an electric induction furnace, the combination of a main chamber in refractory material having a channel communicating with the main chamber, a magnetic core encircling the channel, a primary winding on the core, a pair of electrodes entering said chamber, and adjustable means for connecting a suitable number of turns of the primary winding to said electrodes.
7. A combination electric furnace comprising a main chamber provided with an electrode for forming an arc to the charge

therein and an electrode for completing the arc circuit thru the charge, a channel in refractory material connecting with the main chamber, a magnetic core encircled by said channel, said core having a primary winding thereon, and independent means for connecting a suitable number of turns of the primary winding to a source of alternating current and to the said electrodes respectively.

8. A combination electric furnace comprising a main chamber, a shaft above the same, a channel in refractory material connecting with said main chamber, an electrode entering said shaft and an electrode for contacting with the charge and completing the arc circuit, means of inducing current in the metal in the refractory channel including a magnetic core having a primary winding thereon, means of connecting said primary winding to a source of alternating current, and means of connecting suitable portions of said winding to electrodes.

9. A combination electric furnace comprising an arc heating chamber, an induction heating channel in refractory material connecting with said arc chamber, a magnetic core encircled by said channel, a primary winding on said core, an electrode entering the arc chamber thru the roof thereof, an electrode in the hearth of said chamber, and means of connecting said electrodes to a suitable number of turns of said primary winding.

10. An electric furnace comprising a main chamber, an induction channel opening into said chamber and encircling a magnetic core, an electrode entering the main chamber for generating heat therein, another electrode arranged for completing the arc circuit thru said first electrode, a primary winding on the magnetic core for magnetizing same, said winding and core comprising an auto transformer having terminals which may be tapped onto the electrodes of the arc circuit.

11. An electric furnace comprising a magnetic core, and a primary winding thereon constituting an auto-transformer, a single turn molten metal secondary circuit for heating the charge, and means of taking current from the primary winding and generating additional heat in an arc circuit in proximity to the charge.

12. The combination of an electric furnace having an arc heating chamber with electrodes entering therein, an induction heating channel connecting therewith, a magnetic core encircling said induction channel, a primary winding on said core constituting an auto transformer for supplying current to the electric arc circuit, and means of control consisting of independent means for varying the number of turns of the primary winding connected to the sup-

ply circuit and the number of turns of said winding connected to the electrodes, thereby independently controlling the current induced in the molten metal and the current thru the arc circuit.

13. A combination arc and induction furnace in which the arc circuit and the induction circuit are energized from the same primary winding on a magnetic core attached to said furnace.

14. An induction arc furnace comprising a plurality of magnetic cores, secondary channels in refractory material surrounding each core, primary windings on said cores, a main chamber with which said channels connect, a polyphase supply circuit, means of connecting the separate windings to separate phases of said polyphase supply circuit, means for connecting electrodes in circuit with the windings on said cores, said electrodes entering said main chamber, and means for controlling the voltage applied to the electrode circuit as desired.

15. An induction furnace for operation from a three phase supply circuit, said furnace comprising a plurality of magnetic cores, windings on each of said cores, means for interconnecting said windings to a three phase supply circuit, means for connecting three electrodes entering said furnace to said windings, and means for inducing current in a molten metal secondary circuit in combination with said furnace.

16. The combination with an electric furnace comprising a chamber with electrodes entering the same, of a magnetic core, a winding thereon, a channel encircling said core for containing molten metal, and means of connecting the said winding to said electrodes, and means of connecting said winding to a source of alternating current.

17. A combination arc and induction furnace comprising an arc or resistance, chamber, an induction channel connected to and communicating with said chamber, and means for melting charge in the arc chamber and causing it to enter said channel and have current induced therein, and means for varying the electric energy developed in the arc chamber and in the induction circuit independently.

18. The method of operating an induction arc furnace having two magnetic cores which consists in so connecting the primary windings to a three phase current supply as to keep the three phase load balanced while transforming to two phase in the secondary channels, and when desired, connecting three electrodes to the windings and operating by auto transformer.

19. An electric induction furnace comprising a transformer core, a primary winding thereon, a channel in refractory material encircling said core for containing a molten

metal secondary circuit, a main chamber connected with said channel, electrodes entering said main chamber for heating charge therein, said electrodes being connected to a winding on said transformer core, and means for operating either the electrode circuit or the induction circuit separately or together as desired.

20. An induction furnace comprising a plurality of magnetic cores, secondary channels in refractory material respectively surrounding said cores, primary windings on said cores respectively for magnetizing them, a main chamber for holding a charge, said chamber connected with said channels, means for connecting the separate windings to separate phases of a polyphase circuit, means for connecting an electrode in circuit with windings on each of said cores, means for supporting said electrodes in position to enter the main chamber for generating heat in the charge therein, and means for controlling the voltage induced in the separate circuits of the furnace.

21. An induction furnace for operation from a three phase power circuit, said furnace comprising two magnetic cores, a primary winding on each core, means for interconnecting said primary windings to a three phase circuit, means for connecting three electrodes to the respective windings on the said two magnetic cores, means for supporting electrodes to enter the main chamber, induction channels connected with the main chamber and respectively encircling the said cores, and means for passing three phase current thru the electrodes into the charge in the main chamber at the desired voltage between the electrodes.

22. An induction arc furnace comprising a main chamber, a plurality of magnetic cores, primary windings thereon, channels in refractory material encircling said cores and connecting with the main chamber, means for connecting the windings on the separate cores to separate phases of a polyphase power circuit, electrodes mounted in position to enter said chamber, and means for effecting the generation of heat in said main chamber by passing current thru said electrodes from the windings on said magnetic cores.

23. In combination, in an electric induction furnace, a single turn secondary heating circuit around the core of said furnace, an electrode circuit taking current from a winding on said core, and independent means for regulating the single turn voltage and the electrode voltage.

24. In combination, in an electric induction furnace, a single turn secondary heating circuit around the core of said furnace, and an electrode circuit, comprising one or more movable electrodes entering the chamber of

said furnace and means for regulating the voltage applied to the electrode circuit from a winding on said core.

25. In an electric induction furnace, the combination of three separate interconnected secondary circuits each encircling a magnetic core leg, a primary winding for each secondary circuit, and taps on each of said primary windings for connecting the proper number of turns of each winding between the three conductors of a three phase supply system.

26. In a three phase induction furnace the combination of three single turn secondary circuits, a magnetic core thru each of said circuits, three corresponding primary windings each having taps, and means of connecting the desired number of turns of each winding in star between the three conductors of a three phase supply system, whereby the single turn induced voltage may be regulated.

27. In combination, a three phase induction furnace comprising a three phase magnetic core having three legs extending thru corresponding single turn secondary heating circuits, the ends of said three legs being connected together to complete the magnetic circuits, the number of the channel sections in the plane of the said extending legs being one more than the number of said extending legs.

28. A combination three phase induction furnace, comprising an elongated chamber for holding metal, four channels connecting therewith on one side thereof, the other ends of said channels having a common connecting channel thus forming three single turn circuits, a leg of a magnetic core extending thru each of said circuits, and windings on each of said cores connected to a three phase system.

29. In combination, an arc and induction furnace comprising a main chamber, induction channels connecting therewith and encircling magnetic cores, adjustable electrodes entering said main chamber for heating charge therein, and means for supplying current at the desired voltage to said electrodes from windings on said magnetic cores.

30. An electrode furnace comprising a refractory channel, arranged to hold molten metal, said metal constituting the secondary circuit of a transformer, a chamber associated with said channel and arranged to hold molten metal, and electric heating means in said chamber above the surface of the metal and actuated by said transformer.

31. An electric furnace comprising a refractory channel arranged to hold molten metal, said metal constituting the secondary circuit of a transformer, a chamber associated with said channel and constituting a continuation thereof, and arranged to hold

molten metal, and electric heating means in said chamber above the surface of the metal and actuated by said transformer.

32. An electric furnace comprising a refractory channel arranged to hold molten metal, said metal constituting the secondary circuit of a transformer, a chamber associated with said channel and constituting a continuation thereof and arranged to hold molten metal, the metal in the channel and in the chamber constituting a continuous circuit, and electric heating means in said chamber above the surface of the metal and actuated by said transformer.

33. An electric induction furnace comprising in a main chamber, a loop channel communicating with said main chamber and adapted to receive molten metal from said main chamber, electrodes extending thru the top and bottom of the furnace for effecting heating in said main chamber, and transformer windings and connections for effecting the energization of said magnetic core to induce current in the molten metal in said loop channel and for supplying current to said electrodes to effect heating in said main chamber.

34. An electric induction furnace comprising a three phase transformer core, a winding on each phase of said core, taps on said winding and adjustable means for connecting said windings in star connection to a three phase power circuit.

35. The method of operating an induction furnace, said method consisting in supplying current from a winding on the transformer of said induction furnace to electrodes in a heating chamber, and controlling the electrode voltage and the single turn transformer voltage independently of each other.

36. In an electric induction furnace the combination of a single turn secondary heating circuit of a transformer and an electrode heating circuit supplied with current from the same transformer, and means for controlling the heating in said circuits separately and independently.

37. An electric induction furnace comprising a magnetic core, a winding on said core, an electrode circuit comprising electrodes entering a chamber of said furnace, and circuits and connections for supplying current to said electrode circuit from a winding on said core and for varying the electrode voltage.

38. In an electric induction furnace, the combination with a chamber for containing a charge of metal to be treated, of electrodes entering said chamber, channels adapted to contain molten metal communicating with said chamber and for induction of current therein, a magnetic core encircling one of said channels, and a winding on said core connected to said electrodes.

39. The process of treating charge in an

- electric furnace provided with top adjustable electrodes supplied with current from a variable voltage source, said process consisting in first subjecting the charge to heat from one or more arcs from said electrodes to the charge and subsequently heating the melted charge by means of a lower voltage current thru said charge, and regulating the voltage and current independently. 65
- 10 40. In combination, an electric furnace, two or more magnetic cores, windings thereon, means for connecting said windings to a source of alternating current, and means for connecting said windings to three electrodes entering the chamber of said furnace. 70
- 15 41. In combination with a three electrode electric furnace, a polyphase supply circuit, an auto transformer comprising two or more magnetic cores, windings thereon connected to said polyphase circuit, and connections from said windings to the said three electrodes. 75
- 20 42. In combination, an electric furnace, a polyphase supply circuit, an auto transformer having two or more separate windings interconnected to separate phases of a polyphase circuit, and means of connecting a plurality of electrodes to said windings. 80
- 25 43. In an electric arc furnace, the combination with a furnace chamber having refractory walls, of an arc resistor, an upper electrode adjustable in elevation and in position for melting and heating a charge in said chamber, and a variable voltage source of power connected to said electrode to supply current thru said resistor, and independent means of adjusting the voltage of the circuit supplying the current to said arc circuit. 85
- 30 44. In an electric furnace, a plurality of arcing electrodes, a source of polyphase current comprising a plurality of transformer windings, a circuit connecting each of said windings to a corresponding electrode, said windings having a common or neutral connection, and means of adjusting the number of turns of said windings connected between the common connection and each electrode. 90
- 35 45. A polyphase electric furnace comprising a heating chamber, three adjustable electrodes entering said chamber for arcing to charge therein, a conducting bottom electrode extending thru the hearth of said chamber, and means for supplying a variable voltage between said adjustable electrodes and said bottom electrode, independently of the adjustment of said electrodes. 95
- 40 46. In combination, an induction furnace having a main chamber, two electrodes entering said chamber thru the top and adjustable in elevation, a bottom electrode thru the lining of said chamber for making contact with the charge, two magnetic cores encircling secondary single turn heating circuits and connections from windings on said cores to said top electrodes and said bottom electrode. 100
- 45 47. In combination, an electric furnace, two magnetic cores, windings thereon, means of connecting said windings to a source of alternating current, and means of connecting said windings to three electrodes entering the chamber of said furnace, and single turn secondary heating circuits around said cores. 105
- 50 48. A polyphase induction furnace comprising a magnetic core and winding thereon for each phase, an electrode for each phase entering a chamber of said furnace, and means of connecting each electrode to a winding on each core respectively. 110
- 55 49. In an electric furnace structure, a crucible electric heating means therein, a metal holding conduit in communication with said crucible, a transformer in inductive relation to said conduit, a coil on said transformer, said coil provided with a multiplicity of taps, switch connections to vary the active length of said coil, and other switch connections connected to said heating means and arranged to independently vary the quantity of electric energy supplied to the heating means in the crucible. 115
- 60 50. The process of treating metal in an electric furnace provided with a top adjustable electrode for arcing to the charge, said process consisting in supplying current of comparatively high voltage to form the arc, from said electrode to the charge, and subsequently heating the melted charge by passing a current of lower voltage thru it, and regulating the current independently of the regulation of the voltage applied across the arc. 120
- 65 51. The method of operating an electric furnace, said method consisting in forming an arc of relatively high voltage from an adjustable electrode to the charge and subsequently introducing a lower voltage current through the melted charge and regulating the current independently of the electrode voltage. 125
- 70 52. The method of melting and treating charge in an electric furnace, said method consisting in subjecting the charge first to the action of a high voltage arc and subsequently introducing a lower voltage current thru the molten charge, and regulating the current independently of the electrode voltage. 130
- 75 53. The method of operating a polyphase electric furnace, said method consisting in maintaining a relatively high electrode voltage, maintaining arcs from the electrodes to the charge, and subsequently heating the melted metal by passing lower voltage current therethru, and regulating the electrode voltage and current independently. 135
- 80 54. In apparatus for treating metal by the use of an electric arc, the combination of

5. a pair of electrodes, one of which is movable relatively to the other one, and means for delivering to said electrodes when positioned for a relatively long arc a given kilowatt load, and then substantially the same kilowatt load with reduced voltage and increased amperage when the electrodes are positioned for a shorter arc.
10. 55. In apparatus for treating metal by the use of an electric arc, the combination of a pair of electrodes, one of which is movable relatively to the other one, means for delivering to said electrodes when positioned for a relatively long arc a given kilowatt load, and then substantially the same kilowatt load when the electrodes are positioned for a shorter arc, and a reactance in said electrode circuit.
15. 56. In the manufacture of metals in an arc type electric furnace, the combination with arc electrodes of means for varying the amount of current through the metal bath while maintaining substantially the same k. w. load in the electric circuit.
20. 57. In combination, an electric furnace, a plurality of arcing electrodes, a source of polyphase current, a plurality of transformer windings comprising primary and secondary circuits for each phase, a connection between each of said electrodes and a secondary winding and means of adjusting the number of turns of the primary windings connected to the source of power.
25. 58. In an electric furnace a three phase transformer having secondary circuits connected to the electrodes of said furnace and means of adjusting the number of primary turns in circuit between three conductors of a three phase power supply circuit.
30. 59. In an electric arc furnace the combination with a furnace having an adjustable top electrode for arcing to the charge and another electrode for completing the arc circuit, of a transformer having primary and secondary circuits, the secondary circuit being connected to the electrodes, and means of adjusting the number of turns of the primary in circuit with the power supply.
35. 60. In combination with an electric furnace, an auto-transformer, a relatively constant voltage source of alternating current, means for connecting the desired number of turns of the auto-transformer to this current supply, and means including said auto-transformer for varying the electrode voltage applied to the electrodes of the electric furnace.
40. 61. In combination with an electric arc furnace, a source of alternating current of relatively low voltage such as 440 volts or less, and an auto transformer having taps for varying the voltage applied to the electrodes of said arc furnace.
45. 62. In combination with an electric arc furnace, a source of low voltage alternating current which voltage is near one of the voltages used on the electrodes, and an auto transformer connected to this low voltage alternating current supply circuit for adjusting and varying the voltages applied to the electrodes.
50. 63. In combination with an electric arc furnace, a source of alternating current for supplying power to the electrodes, an auto transformer having a winding connected to said alternating current supply and another winding connected to the electrodes and means for applying different voltages between the electrodes.
55. 64. In combination with an electric arc furnace, a source of relatively low voltage alternating current for operating said arc furnace, a polyphase auto transformer, means for connecting the primary windings of said auto transformer to the said supply and means for arranging the phases and windings so as to furnish different voltages to the electrodes of said arc furnace.
60. 65. In combination, a three phase electric arc furnace having three electrodes adjustable in elevation, a source of low voltage alternating current supply, an auto transformer having primary windings for connecting to the different phases of the three phase supply and having connections from windings to the electrodes of said arc furnace, and means for changing the connections to change the voltage applied to the electrodes.
65. 66. In combination with an electric arc furnace, a source of alternating current supply, a magnetic core and windings thereon for connection to the alternating current supply and to the electrodes of said arc furnace, means for connecting different taps to the supply or electrode circuits and said arrangement of windings on said core being such as to introduce magnetic leakage in more than normal amounts into the circuit supplying current to the electrodes.
70. 67. In combination with an electric furnace, a source of alternating current power for supplying current to the terminals of said furnace, a booster transformer having a winding in series between a terminal of said furnace and the power supply circuit, and means of energizing the booster transformer.
75. 68. In combination with an electric furnace, a source of alternating current power for supplying current to the terminals of said furnace, a transformer having a relatively low voltage winding in series between the power supply circuit and a terminal of the furnace, and means for connecting a winding on said transformer between the lines of said power supply circuit.
80. 69. In combination with an electric furnace having electrodes, a source of alternating current power for supplying cur-

rent to said electrodes, a separate transformer having a winding in series between the supply circuit and an electrode and means for controlling the voltage induced 5 in said transformer winding.

70. In combination with an electric furnace having a plurality of electrodes, a source of alternating current power, a low voltage transformer secondary winding in series be- 10 tween each electrode of said furnace and a phase of said alternating current supply circuit and means for controlling the voltage induced in said secondary windings.

71. In combination with an electric fur- 15 nace, two separate induced voltages in circuit in series with each other and with the electrodes of said furnace, and means for controlling the relative direction of induced voltage in one circuit with respect to the 20 other.

72. The combination with an electric fur- 25 nace of means for supplying current to the terminals of said furnace thru an auto transformer, means for varying the induced voltage in the windings of said auto trans- 30 former and means for connecting the desired taps to the furnace terminals.

73. The combination with an electric fur- 35 nace of a transformer supplying current to said furnace, a booster transformer having a winding in series between the power supply and the furnace, and means for connecting the booster transformer primary between the power supply lines for controlling the induced current.

74. In combination with an electric fur- 40 nace, a source of alternating current power for supplying current to the terminals of said furnace, a booster transformer having a secondary winding in series between the fur- 45 nace terminal and the power supply, and a primary winding for said booster, this latter connected so as to control the direction of the booster secondary voltage in relation to that of the supply circuit.

75. In combination with the electrodes of an electric arc furnace, a transformer core, primary and secondary windings thereon, taps on said windings whereby a comparatively high voltage may be impressed on 50 the secondary circuit for maintaining an arc, reactance in the secondary circuit, and taps on the windings for impressing a lower voltage on the secondary circuit to the electrodes. 55

76. The method of melting and refining metal in an electric furnace, which method consists in supplying current of comparatively high voltage to the electrodes thru a reactance in the electrode circuit and maintaining an arc with said relatively high voltage. 60

77. The combination with an electric fur- 65 nace having a plurality of electrodes, of a three phase transformer having both primary and secondary windings connected in star, both of said windings having series of taps whereby the voltage applied to the electrodes may be varied. 70

78. In combination with the electrodes of an electric furnace, a three phase transformer set having taps on the primary and secondary windings of each phase, means for connecting any given primary tap on each phase to the corresponding phase of an 75 alternating current supply circuit, and means for connecting any given tap on the secondary part of each phase to a corresponding electrode of said furnace to regulate the electrode to electrode voltage. 80

79. The combination of an electric arc fur- 85 nace, a three phase transformer system having secondary windings connected together in star and having a conductor leading from the neutral connection to the furnace bottom, and means for changing the connections to vary the secondary voltage on the electrodes.

ALBERT E. GREENE.
